UNITED STATES PATENT OFFICE.

EDWARD E. PINKERTON, OF CHICAGO, ILLINOIS, ASSIGNOR OF ONE-HALF TO JOSHUA R. H. POTTS, OF CHICAGO, ILLINOIS.

DISPLAY BOX.

Application filed March 18, 1922. Serial No. 544,122.

To all whom it may concern:

Be it known that I, EDWARD E. PINKERTON, a citizen of the United States, and a resident of the city of Chicago, county of Cook, and State of Illinois, have invented certain new and useful Improvements in Display Boxes, of which the following is a specification.

My invention relates to improvements in display boxes, and has for its object the provision of an improved construction of this character adapted and arranged to display one of the articles contained therein which is of simple construction, efficient in use, and capable of use for displaying articles of considerable size.

Other objects will appear hereinafter.

The invention consists in the combinations and arrangements of parts hereinafter described and claimed.

The invention will be best understood by reference to the accompanying drawings forming a part of this specification, and in which,

Fig. 1 is a plan view of a box blank for making a box embodying the invention;

Fig. 2 is a perspective view of the box assembled;

Fig. 3, an end view, of the same;

Fig. 4, a side view, of the same; and

Fig. 5, a face view, of the same.

The preferred form of construction as illustrated in the drawings comprises a blank formed into four consecutive box sides, 6, 7, 8 and 9 adapted and arranged to be folded to form a tubular collapsible box, the side wall 6 being provided with a flap 10 which is secured to the inner side of the wall 9 for this purpose. The walls 6, 7, 8 and 9 are provided with the usual sealing flaps at their ends and whereby the ends of the box may be closed in the usual manner. The side wall 9 is provided with a strip 11 having a head 12 as shown and the side wall 6 is provided with slits 13 and 14 as shown. The slits 13 are arranged in two sets or pairs of parallel slits and through which

the strip 11 is adapted to be laced as indicated in order to form a retainer for a tooth brush 15 or the like. The head 12 of the strip 11 is inserted in the slit 14, thus locking the strip in place. By this arrangement a simple and effective construction is provided which is capable of economical manufacture and which may be employed for displaying articles of considerable size such as tooth brushes, hat brushes, and the like.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A display box comprising a foldable box body; and a flexible strip secured at one end of said body, there being slits formed in said body through which the free end of said strip is laced to form a retainer for holding an article to be displayed.

2. A display box comprising a foldable box body; and a flexible strip formed integral with one side of said body and provided at its free end with a locking head, there being two sets of parallel slits formed in an adjacent side of said body through which the free end of said strip is laced to form a retainer for holding an article to be displayed, there being another slit to receive the head on the end of said strip.

In testimony whereof I have signed my name to this specification in the presence of two subscribing witnesses.

EDWARD E. PINKERTON.
